UNITED STATES PATENT OFFICE

2,024,484

GOLF CLUB RACK

Anthony Smith, Syracuse, N. Y.

Application September 20, 1934, Serial No. 744,829

3 Claims. (Cl. 150—1.5)

This invention relates to golf club carrying means and more particularly to a golf club rack which is of a relatively light nature and which is so constructed as to hold the golf clubs in spaced apart relation to each other so that the shafts of the clubs will not be injured by the clubs striking one another as is the case with conventional golf club bags.

An object of this invention is to provide a golf club carrying means of this character which is exceedingly simple in construction and which also includes means whereby the clubs may be supported in an upright position when the player has removed one club from the device.

Another object of this invention is to provide a rack structure of this character which also supports a number of golf balls and tees which may be readily removed for use in playing the game of golf.

A further object of this invention is to provide a structure of this kind which is exceedingly light in weight so that the desired number of clubs may be carried together with other paraphernalia used in the playing of the game.

The above and various other objects and advantages of this invention will in part be described and in part be understood from the following detailed description of the present preferred embodiment, the same being illustrated in the accompanying drawing wherein:

Figure 1 is a side elevation partly in section of a device constructed according to the preferred embodiment of this invention.

Figure 2 is a bottom plan view partly in section taken on the line 2—2 of Figure 1.

Figure 3 is an enlarged fragmentary sectional view taken on the line 3—3 of Figure 1.

Referring to the drawing, the numeral 10 designates generally an upper plate and the numeral 11 designates generally a lower plate forming part of a rack structure for holding golf clubs, generally designated as C. The plates 10 and 11 are held in spaced apart relation by means of a spacing bar 13, which may be either welded or otherwise attached to the confronting faces of the plates 10 and 11. These plates 10 and 11 are substantially alike and each plate is provided with a plurality of outwardly opening notches or slots 12 adapted to loosely receive therein shafts of the golf clubs C with the head of the club C above the upper plate 10. The plates 10 and 11 on the lower side thereof each have clamping devices for releasably holding the clubs C in the slots 12, and these clamping devices are constructed in the form of clamping arms 14 which are integral with each other, being formed from a single sheet of relatively yieldable material and having flared and spaced apart outer portions 15 to facilitate the insertion of the shaft of the club C therein.

The inner or base portion 16 of each clamp 14 has secured thereto a base plate 17 which in turn is fastened as by welding or other suitable fastening means to the under side of the plate 10. The club clamping means on the plate 11 are also fastened on the under or lower side of the plate 11.

The clamping members 14 are also tensioned by means of spring members 18 engaging the outer sides of the clamping members 14 and secured as by soldering, welding or the like, to the inner stem portion 16 of the clamping members 14. There are as many slots 12 and clamping members 14 in the plates 10 and 11 as are deemed necessary to secure the desired number of golf clubs to the rack structure. It will, therefore, be understood that I do not wish to be limited to any number of slots 12 and clamping members 14, as the number may be varied with the size of the plates 10 and 11 and the desires of the user of the device.

The plates 10 and 11 are also held in spaced apart relation by means of a pair of bracing members or rods 19 which are secured at one end to the under side of the plate 10 and at the other end to the upper side of the plate 11 as by welding, riveting or any other suitable fastening means. Preferably, the rods or bracing members 19 have their central portion 20 disposed outwardly of the edges of the plates 10 and 11, and a tubular tee holding member 21 is secured to this offset portion 20.

The tee supporting member 21 is constructed in the form of a metal tube open at each end and in order to prevent the dropping of the tees out of the tube 21, this tube 21 is provided with a pair of tee holding members 22 which are of a yieldable construction and preferably are formed by striking the members 22 from the tube 21 and forcing the material inwardly so as to engage the shanks 23 of the lowermost tee in the tube 21. If desired, there may be a tee holding member 22 at the lower and also at the upper end of the tube 21. The tees are removed from the tube 21 by pulling the shaft 23 thereof of the lowermost tee downwardly.

A golf ball supporting means is provided in the rack structure herein disclosed by mounting a tube 24 between the plates 10 and 11 preferably at the point opposite from the tee holding member 21. This golf ball supporting means in the form of the tube 24 is also provided with a plurality of elongated slots 25 so that the number of balls B in the tube 24 may be readily seen. Preferably the lower plate 11 has an opening 26 therethrough large enough for the balls B to pass therethrough and the balls B are releasably held in the tube 24 by means of a spring clip or holding member 27 which projects below the plate 11 so that a portion of the lowermost ball B will project through the hole 26. This clip 27 has the lower

end thereof bent backwardly a slight degree so that it may be grasped by a finger to swing the clip 27 into a position for releasing one or more of the balls from the container 24.

5 The rod or bracing member 18 at its lower end is provided with a threaded opening 28 in which is received a threaded stud 29 carried by the upper end of a rack supporting standard or member 30. This standard 30 has a reduced point or ground 10 piercing member 31 at its lower end and the standard 30 is preferably of a length such as to hold the entire rack structure with the clubs mounted thereon a slight distance above the surface of the ground. When the post or standard 15 30 is not in use, it may be detachably held in the rack structure by disposing the post 30 through an opening 32 in the lower plate 11 and threading the stud 29 into a nut 33 carried by the under side of the upper plate 10. When the post or standard 20 30 is in this position, the lower end or point 31 will be shorter than the lengths of the clubs disposed in the rack so that the supporting standard or post 31 will not interfere with the carrying of the clubs.

25 The upper plate 10 has a loop 34 secured thereto and the lower plate 11 has a loop 35 secured thereto, and a carrying strap 36 engages these loops 34 and 35, so that the device may be conveniently carried over the shoulder of the player or may be carried in the hand, if desired, by either grasping the strap 36 or grasping the tee holding tube 21, which may be construed as a relatively rigid handle.

30 When the rack structure is resting on the ground, the upper plate 10 may be supported upwardly from the ground by means of legs 37 carried by one edge of the plate 10, and secured thereto as by welding or any other suitable fastening means.

35 In the use of the rack hereinbefore described, the shaft of the club C is engaged with the clamping members 14 of the upper and lower plates 10 and 11, respectively, with the head of the club C above the upper plate 10 and the handles extending down below the lower plate 11. The device 40 with the clubs C therein may be carried either in the hand or over the shoulder by the strap 36, and when the player desires to remove a club from the rack for use in playing the game of golf, the club may be pulled out of the slot 12 and the rack with the remaining clubs therein may be supported in an upright position by projecting the point 31 into the ground, it being understood 45 that the standard or post 30 has the threaded stud 29 in the socket or opening 28 of the bar 12. Balls may be removed from the container 24 by 50 pressing the clip or yieldable holding member 27 outwardly, and a tee may be removed from the tee holding member 21 by pulling the stem portion 55 23 of the tee downwardly from the lower end of the tee container 21. After the lowermost tee has 60 been pulled out of the container 21, the next succeeding tee will drop downwardly and will be held with the stem portion thereof projecting below 65 the bottom of the container 21 for use when desired. The rack structure hereinbefore described 70 also includes a clamp or spring pressed member, generally designated as 38, which is secured to the ball container 24 and which includes a card clamp 39 for holding a score card and a pencil clamp 40 for releasably holding the pencil used

in scoring the strokes made in the playing of the game.

The device hereinbefore described may be constructed out of relatively light material and due to the relatively small number of parts comprising the device, it may not only be constructed cheaply but constructed very lightly, so that a considerable number of clubs may be carried without inconveniencing the player on account of the weight of the device as is the case in leather or other golf bags at present in use which hold a number of clubs, balls and other material.

The rack hereinbefore described also has a clip or spring pressed member 41 secured to the lower plate 11 for holding a towel 42.

What is claimed is:—

1. A golf club rack, comprising upper and lower plate members each having a plurality of marginal notches therein to loosely receive the shafts of golf clubs, means for holding the plate members in spaced apart relation, said means including a hollow member having communication through one of said plate members, said hollow member receiving golf balls therein, means for releasably holding golf balls in said hollow member, a second hollow member, and means for supporting said second hollow member between the plate members, said latter means coacting with said first hollow member in maintaining said plate members in spaced apart relation and also maintaining said second hollow member in offset relation to said plate members, said second hollow member constituting a handle.

2. A golf club rack comprising upper and lower plate members, each having a plurality of marginal notches therein to loosely receive the shafts of golf clubs, means for holding the plate members in spaced apart relation, said means including a hollow member having communication through one of said plate members, yieldable means carried by at least one plate member for clamping the shafts of golf clubs in said notches, said hollow member receiving golf balls therein, means for releasably holding golf balls in said hollow member, a second hollow member, and means for supporting said second hollow member between the plate members, said latter means coacting with said first hollow member in maintaining said plate members in spaced apart relation and also maintaining said second hollow member in offset relation to said plate members, said second hollow member constituting a handle.

3. A golf club rack comprising upper and lower plate members, each having a plurality of marginal notches therein to loosely receive the shafts of golf clubs, means for holding the plate members in spaced apart relation, said means including a hollow member having communication through one of said plate members, yieldable shaft holding means secured to each plate for holding the shafts of golf clubs in said notches, said hollow member receiving golf balls therein, means for releasably holding golf balls in said hollow member, a second hollow member, and means for supporting said second hollow member between the plate members, said latter means coacting with said first hollow member in maintaining said plate members in spaced apart relation and also maintaining said second hollow member in offset relation to said plate members, said second hollow member constituting a handle.

ANTHONY SMITH.
